United States Patent Office

Des. 193,892
Patented Oct. 23, 1962

193,892

BUILDING BLOCK

Hollis L. Clanton, Sun Valley, Calif., assignor, by mesne assignments, to Kaiser Steel Corporation, Oakland, Calif., a corporation of Nevada

Filed Dec. 23, 1958, Ser. No. 53,883

Term of patent 14 years

(Cl. D18—2)

FIG. 1.

FIG. 2.

FIG. 3.

FIG. 4.

FIG. 1 is a perspective view of a building block showing my new design;

FIG. 2 is a front elevational view thereof;

FIG. 3 is a side elevational view thereof; and

FIG. 4 is a plan view thereof.

I claim:

The ornamental design for a building block, substantially as shown.
